MATERIAL CLASSIFIER

George B. Ebersole, Akron, and Lester L. Leach,
Barberton, Ohio, assignors to The Babcock &
Wilcox Company, Rockleigh, N. J., a corpora-
tion of New Jersey

Application April 2, 1943, Serial No. 481,518

4 Claims. (Cl. 209—139)

1

The present invention relates in general to the construction and operation of stationary classifiers adapted to selectively separate solid particles in suspension in a gas stream, and more particularly to classifiers of this type adapted for use in the outlet end of pulverizers in which the pulverized material is carried out of the pulverizing or grinding zone in suspension in a gaseous carrier medium. The classifier of our invention is particularly designed and especially useful in pulverizers of the general type shown in U. S. Patent No. 2,275,595, in which the material treated is coal, phosphate rock, and the like. In such pulverizers, the pulverizing elements are relatively movable upper and lower grinding rings between which a circular row of grinding balls is horizontally arranged, and the pulverized material is removed from the grinding zone by an annular stream of carrier air passing upwardly through a restricted annular throat and picking up pulverized material discharged from the outer circumferential edge of the lower grinding ring.

The general object of our invention is the provision of a material classifier which is capable of effectively classifying suspended material at high capacity rates with a relatively low pressure drop through the classifier. A further and more specific object is the provision of an air-swept pulverizer having a classifier of the type described which is capable of substantially increasing the circulating load of the pulverizer while substantially reducing the air pressure drop through the grinding zone.

The various features of novelty which characterize our invention are pointed out with particularity in the claims annexed to and forming a part of this specification. For a better understanding of the invention, its operating advantages and specific objects attained by its use, reference should be had to the accompanying drawings and descriptive matter in which we have illustrated and described preferred embodiments of our invention.

Of the drawings:

Fig. 1 is a sectional elevation of a pulverizer incorporating a stationary classifier constructed and arranged in accordance with our invention;

Fig. 2 is an enlarged horizontal section, partly broken away, taken on the line 2—2 of Fig. 1; and

Fig. 3 is a sectional elevation of a portion of a pulverizer with a modified form of classifier, parts of the pulverizer being omitted for purposes of clarity.

The classifier of our invention is illustrated in Figs. 1 and 2 as incorporated in the top or out-

let section of an air-swept pulverizer, the grinding parts of which are enclosed in a cylindrical casing 10. The pulverizer has a vertical drive shaft 11 carrying a generally conical drive yoke 12 on its upper end. A lower grinding ring 14 is mounted on flattened lower portions of the yoke and its surface shaped to form a track for a circular row of grinding balls 15. The balls 15 support a non-rotary upper grinding ring 16. An annular spider 17 mounted on the upper ring is provided with lugs 18 arranged in vertical guides 19 on the inner wall of the casing 10 for preventing rotation, but permitting vertical movement, of the spider and upper ring. A resilient grinding pressure is exerted downwardly on the grinding parts by a number of coil springs 20 engaging the spider.

The material to be pulverized is supplied through a feed spout 21 to the inner side of the spider and upper grinding ring and falls on the inclined upper surface of the drive yoke 12, being distributed throughout the grinding area by the rotation of the drive yoke and associated parts. The material flows outwardly over the upper surface of the yoke and lower grinding ring, is pulverized between the relatively moving balls and grinding rings, and discharges over the outer edge of the lower grinding ring at an oblique angle to the periphery thereof depending upon the ring speed.

The pulverizer disclosed is of the air swept type having an annular stream of primary or carrier air passing upwardly at the discharge side of the pulverizer grinding zone and through a stationary classifier hereinafter described to a central outlet 22 for the material laden air stream. A cylindrical turret 23 forms an upward continuation of the outlet opening 22 and has one or more valve controlled discharge pipes 24 symmetrically connected into the turret top plate. The carrier air is normally preheated and supplied under pressure by a suitable forced draft fan (not shown) to an involute wind box 25 surrounding the casing 10 opposite the grinding zone. The carrier air flows into the pulverizer through casing passages 26 at the outer side of the drive yoke and then upwardly through an annular throat passage 27 formed between the outer side of the lower grinding ring and an annular throat plate 28 mounted on the inner side of the casing. Relatively unpulverizable material, such as pyrites, leaving the grinding zone drops through the throat and is collected in a compartment 29 in the base section of the pulverizer.

The material leaving the pulverizing zone includes a large percentage of oversize or coarse

particles which must be returned to the pulverizing zone for regrinding, if the material distribution to the discharge pipes is to be of the desired fineness and uniformity. Various types of classifiers of various degrees of effectiveness have been installed between the pulverizer grinding zone and discharge pipes for the purpose of selectively classifying the suspended material and returning oversize particles to the grinding zone. A relatively high percentage of returned material or "circulating load" is desirable for optimum operation of pulverizers of this type. The return of rejected oversize particles to the grinding zone is hindered by the varying air pressure conditions in different parts of the pulverizer, and particularly by the pressure drop through the classifier, necessitating the passage of rejected material from a low pressure zone to a higher pressure zone. A further normal obstruction to the return of rejects is the travel of the rejected particles across the path of flow of the material laden air stream approaching the classifier, which tends to cause previously rejected particles to be swept up and again passed through the classifier without intervening regrinding.

The improved classifier of our invention is of the stationary type and comprises a pair of frusto-conical members or truncated cones 30 and 31 arranged coaxially of the pulverizer outlet 22. The outer cone 30 has a top flange 32 held in contact with the pulverizer casing top plate by eye bolts 33 extending through the top plate. The flange extends inwardly from the outer cone to the perimeter of the outlet 22. The inner cone 31 is spaced from the outer cone a distance equal to the width of the flange 32, with its upper end spaced therefrom to provide an annular opening 34 into the downwardly flaring annular space 35 between the cones.

The lower part of the space within the inner cone 31 is occupied by a central hub or cover member 37 and a series of symmetrically arranged overlapping inclined segmental blades 38 extending radially from the hub 37 to the inner side of the lower end of the inner cone 31. Each of the blades 38 is inclined in a clockwise direction. Twelve blades are shown and each blade when developed has a true angle of 40°, so that a considerable overlap of adjacent blades is provided.

The annular opening 34 at the upper end of the intercone space 35 is occupied by a circular series of short inclined deflector plates 40 symmetrically spaced circumferentially. Sixteen of such plates are used in the embodiment illustrated, each being inclined 45° in both plan and elevation, with the outer edge advanced in a clockwise direction. The space 35 between the cone members is divided into three double chutes by inclined plates 42, the lower end of each chute opening into a depending trap 43 having a hinged flap valve or gate 44 at its lower end. The traps 43 are inclined inwardly sufficiently to bring their lower ends above the inner side of the ball row. A portion of the outer cone 30 is cut away to avoid obstructing the feed spout 21.

The effective flow area of the annular opening 34 is made variable by a sleeve 46 positioned in the lower end of the turret and adapted to be moved downwardly, as indicated in broken lines, to close off all or a part of the opening 34. Externally adjustable support rods 47 are provided for this purpose.

When a pulverizer of the character described is used in a direct fired pulverized coal system, the

amount of carrier air supplied is substantially directly proportional to the amount of coal to be pulverized. The air velocity in the throat will vary with changes in load, but at all times will be sufficient to lift the pulverized material out of the pulverizing zone. Normally a mass of pulverized material will be maintained in a floating condition above the throat and from which the rising air stream continuously picks up pulverized material. The clockwise rotation of the pulverizer yoke and lower grinding ring tends to promote a swirl of the material laden air in that direction, so that the stream passing upwardly along the outer side of the upper grinding ring and spider will have a general clockwise movement. In order to reach the pulverizer outlet 22, the material laden air stream must pass through the passages formed between the stationary blades 38 and due to the shape and inclined arrangement of these blades receives a substantial additional swirling effect in a clockwise direction which causes the larger size particles to be thrown outwardly toward the converging boundary wall 31. As the stream moves upwardly in a substantially helical path the larger particles tend to assume positions along the periphery of the stream under the centrifugal effect imposed thereon and as the stream of air-borne material reaches the level of the annular opening 34, the larger size particles move outwardly into the opening and in effect are skimmed off the moving stream by the plates and enter the space 35, thereby increasing the average fineness of the remaining particles in suspension. The amount of material so eliminated is proportional to the effective port area of the opening 34, so that the sleeve 46 can be adjusted to control that area and thereby the effective time in which the oversize particles can separate from the stream. The fineness of the suspended material passing to the turret and discharge pipes is thus variable.

The annular opening 34 also acts as an outlet for oversize material separating out of the stream when in the turret. Due to the substantial height and cylindrical shape of the turret, eddy currents tend to form in the upper part thereof, which together with the retarding action of the turret walls, have been found to effect further separation of the larger size particles. These oversize particles dribble down the sides of the turret wall and control sleeve and pass out through the annular opening 34.

The oversize or rejected material entering the intercone space 35 falls down the chutes therein to the traps 43, from which it discharges through the flap valves whenever the head of material is sufficient to overcome the existing pressure differential between the pulverizing zone and the interior of the classifier. The rejected material drops into the space at the inner side of the ball row and again passes through the pulverizing zone.

The described construction and arrangement of the classifier has been found to result in the maintenance of a desirably high circulating load in the pulverizer, while reducing the amount of material in flotation above the throat substantially to the minimum necessary to operate the usual differential pressure control of the associated feeder. The selective separation obtained with the described classifier is highly effective in eliminating oversize material with little, if any, added fan power consumption.

In the modification illustrated in Fig. 3, the overall height of the classifier is substantially

increased and the level of the reject opening raised to more effectively utilize the swirl effect created by the stationary blades 38. The general arrangement is similar to that in Figs. 1 and 2, with the body of the classifier formed by spaced inner and outer truncated cones 50 and 51 respectively enclosing an annular space 52 divided into chutes by inclined plates 53 leading into flap valve controlled bottom traps 54. The turret 60 is flared upwardly and the inner cone member 50 provided with an upwardly flaring extension 61 to provide a continuation of the space 52. The upper end of the turret has a top plate 62 in which discharge pipes 63 are symmetrically arranged. The inner cone extension 61 stops short of the top plate 62 to provide an annular exit opening 65 for the rejected material into the annular space 52. An inverted frusto-conical baffle 66 is positioned at the inner side of the exit opening 65 to facilitate the separation of material flowing along the surface of the extension member 61, while requiring an abrupt change in direction of material in the peripheral portion of the stream to reach the discharge pipes 63. The baffle 66 is supported from the top plate 62 by rods 68 which are externally adjustable to vary the position of the baffle and thereby the effective entrance area of the exit opening 65. The higher the position of the cone, the greater will be the fineness of the material reaching the discharge pipes.

While in accordance with the provisions of the statutes we have illustrated and described herein the best forms of the invention now known to us, those skilled in the art will understand that changes may be made in the form of the apparatus disclosed without departing from the spirit of the invention covered by our claims, and that certain features of our invention may sometimes be used to advantage without a corresponding use of other features. In the claims, the word "air" is intended to generically cover any gaseous carrier medium suitable for removing pulverized material in the manner described.

We claim:

1. A material classifier comprising a pair of vertically extending inner and outer upright frusto-conical casing members arranged to form an annular space therebetween and inlet and outlet openings for air-borne material at the lower and upper ends respectively of said inner casing member, the upper part of said inner casing member being formed to provide a separate substantially annular entrance for oversize material into said annular space, stationary baffle means in said inlet opening constructed and arranged to swirl the entering air-borne material upwardly through said inner casing member, a vertically adjustable baffle for varying the effective height of said annular entrance, means subdividing at least the lower portion of said annular space into chutes, and a valve controlled trap at the lower end of each chute.

2. A material classifier comprising a pair of vertically extending inner and outer upright frusto-conical casing members arranged to form an annular space therebetween and inlet and outlet openings for air-borne material at the lower and upper ends respectively of said inner casing member, the upper part of said inner casing member being formed to provide a separate substantially annular entrance for oversize material into said annular space, means in said inlet open-

ing for swirling the entering air-borne material upwardly through said inner casing member, deflector plates in said annular entrance for deflecting material into said annular space, means for varying the effective area of said annular entrance, means subdividing at least the lower portion of said annular space into chutes, and a valve controlled trap at the lower end of each chute.

- 10 3. A material classifier comprising a pair of vertically extending inner and outer upright frusto-conical casing members arranged to form an annular space therebetween and inlet and outlet openings for air-borne material at the lower and upper ends respectively of said inner casing member, the upper part of said inner casing member being formed to provide a separate substantially annular entrance for oversize material into said annular space, stationary baffle means in said inlet opening constructed and arranged to swirl the entering air-borne material upwardly through said inner casing member, deflector plates in said annular entrance for deflecting material into said annular space, a vertically adjustable baffle for varying the effective area of said annular entrance, means subdividing at least the lower portion of said annular space into chutes, and a flap valve controlled trap at the lower end of each chute.

- 15 4. In combination, a casing having an outlet in its upper end for material-laden air, and a stationary classifier positioned in said casing below and symmetrically arranged relative to said outlet, said classifier comprising spaced inner and outer upright frusto-conical members relatively arranged to form an annular space therebetween having an annular opening thereto above said inner frusto-conical member, stationary baffle means within said inner frusto-conical member constructed and arranged for effecting a swirl of entering material-laden air, deflector plates positioned in said annular opening and arranged to deflect material into said annular space, plates subdividing said annular space into chutes, a flap valve controlled trap at the bottom of each chute, and an adjustable sleeve baffle arranged to vary the effective area of said annular opening.
